Specification for Design.

Patented June 28, 1921.

Application filed October 18, 1920. Serial No. 417,852. Term of patent 7 years.

To all whom it may concern:

Be it known that I, WILLIAM J. HINES, a subject of the King of Great Britain, and a resident of Hartford, in the county of Hartford and State of Connecticut, have invented a new, original, and ornamental Design for a Crumbing Implement, of which the following is a specification, reference being had to the accompanying drawings, forming part thereof, in which—

Figure 1 is a plan view of a crumbing implement showing my new design.

Fig. 2 is an edge view of the same.

Fig. 3 is a view in central cross section through the same.

I claim:

The ornamental design for a crumbing implement, as shown.

WILLIAM J. HINES.
